(57) **CLAIM**

The ornamental design for a display screen with an animated graphical user interface for medical software, as shown and described.

DESCRIPTION

FIG. 1 is a first image of a display screen with an animated graphical user interface for medical software showing the new design;

FIG. 2 is a second image thereof;

FIG. 3 is a third image thereof;

FIG. 4 is a fourth image thereof;

FIG. 5 is a fifth image thereof;

FIG. 6 is a sixth image thereof; and,

FIG. 7 is a seventh image thereof.

The broken lines showing a display screen and portions of the graphical user interface illustrate portions of the article and form no part of the claimed design.

The appearance of the animated graphical user interface transitions from FIGS. 1-7. The process or period in which one image transitions to another forms no part of the claimed design.

1 Claim, 7 Drawing Sheets

Matter enclosed in heavy brackets [ ] appears in the original patent but forms no part of this reissue; matter printed in italics indicates the additions made by reissue.
